UNITED STATES PATENT OFFICE.

JOSEPH C. HACKER, OF NEW YORK, N. Y.

DESIGN FOR A SATCHEL-BODY.

SPECIFICATION forming part of Design No. 15,088, dated June 24, 1884.

Application filed April 24, 1884. Term of patent 3½ years.

To all whom it may concern:

Be it known that I, JOSEPH C. HACKER, of the city, county, and State of New York, have invented a new and original Design for Bag and Satchel Bodies, of which the following is a full, clear, and exact description, reference being had to the accompanying drawing, making part of this specification.

The design relates to a body for satchels and bags; and it consists of a satchel or bag body having ornaments representing a Roman chariot, intertwining arabesques, dragons, and other fanciful figures on a stippled ground.

A in the drawing represents the central ornament in my design for the bodies of satchels and bags, which ornament represents a Roman chariot. Around the chariot A are arabesques B B, which intertwine with fanciful

figures C. The chariot, arabesques, and figures are shown upon a stippled ground. 20

The design imparts to the bag and satchel body a very ornamental and rich appearance.

Having thus described my invention, I claim as new and desire to secure by Letters Patent—

The design for a satchel or bag body composed of the representation of a Roman chariot at the center, dragons and other fanciful figures, and intertwining arabesques, as shown and described. 25

In testimony that I claim the foregoing as my invention I have signed it this 17th day of April, 1884.

JOSEPH C. HACKER.
